[57] ABSTRACT

A type carriage of a single element typewriter is movable in a letter feed direction under the control of an escapement mechanism having interchangeable escapement racks of different pitches for use with interchangeable print elements having type characters requiring different character spacing. A tabulating mechanism having a character spacing corresponding to only one of the interchangeable escapement racks is useable with the alternate escapement rack by supporting a tab member for movement relative to the movable carriage and providing a tab control member for imparting an oscillatory movement to the tab member during a tabulating operation so that the tab member will engage set tab stops at positions corresponding to the pitch of the alternate escapement rack.

TABULATING MECHANISM FOR A DUAL PITCH ESCAPEMENT

This invention relates to a tabulating mechanism for a typewriter or similar business machine, and more particularly to a tabulating mechanism for a single element typewriter capable of utilizing interchangeable print elements having type characters of different character spacing.

In a typewriter or similar business machine, a carriage is slidably mounted on a typewriter frame for enabling relative movement between the printing apparatus and a recording medium supported on a suitable platen, and a line of type is printed by moving the carriage in a letter feed direction in incremental steps each corresponding to the size of the type characters being printed. As is conventional, the stepping movement is effected by an escapement mechanism which includes a rack having a series of teeth with a pitch corresponding to the size of the type characters being printed. In addition, the typewriter is provided with a tabulating mechanism for disengaging the escapement mechanism and effecting a free sliding movement of the carriage in the letter feed direction to a predetermined position whereupon the movement of the carriage is arrested and returned to the control of the escapement mechanism. Typically, the tabulating mechanism includes a tab rack having a plurality of tabs which may be set to stop the carriage during a tabulating operation and each of the tabs represent a position along the line of type corresponding to a tooth of the escapement rack.

As is known, printing with a single element typewriter may be effected utilizing interchangeable print elements having different type styles, numbers, symbols or combinations thereof. Moreover, the interchangeable print elements may have type characters of different sizes, for example elite and pica which require character spacing along a line of type of 2.12 mm. and 2.54 mm. respectively. However, a change of print elements involving a change in character spacing also requires a modification of the escapement mechanism so as to bring into operation an escapement rack having teeth with a pitch corresponding to the character spacing of the print element. Such a modification of the escapement mechanism, however, creates a difference between the character spacing of the escapement mechanism and the character spacing of the tabulating mechanism which may result in tabulating errors.

In the past, single element typewriters capable of utilizing interchangeable type elements of different character spacings have been provided with alternate escapement racks and a tabulating mechanism capable of operating with either escapement rack. Such an arrangement is shown, for example, in German published application DT-AS 1,815,871 and corresponding U.S. Pat. No. 3,540,565 and includes a tabulating mechanism having settable tabs spaced apart at varying intervals. However, such an arrangement is costly, difficult to manufacture and subject to tabulating errors due to the different space intervals between the tabs. Accordingly, an object of the present invention is to provide a tabulating mechanism having tab stops evenly spaced along a tab rack and operable in conjunction with an escapement mechanism capable of effecting escapement movements corresponding to type characters of different sizes.

Another object of the invention is to provide a tabulating mechanism having evenly spaced tab stops corre-

sponding to a particular character spacing and capable of compensating for a difference in pitch with a cooperating escapement mechanism.

Still other objects, features and advantages of the present invention will become apparent to those skilled in the art from a reading of the following detailed description of a single embodiment of the invention, taken in conjunction with the accompanying drawing, wherein:

10 FIG. 1 is a diagrammatic view of a tabulating mechanism constructed in accordance with the present invention and illustrating in a rest position an escapement mechanism having a pitch corresponding to the type character spacing of the tabulating mechanism;

15 FIG. 2 is a view similar to FIG. 1 and illustrating the tabulating mechanism undergoing a tabulating operation in conjunction with an escapement rack having a pitch unequal to the character spacing of the tabulating mechanism;

20 FIG. 3 is a view similar to FIG. 2 and illustrating the operation of a tabulating mechanism upon engagement with a settable tab; and

25 FIG. 4 illustrates diagrammatically the manner in which the tabulating mechanism compensates for the difference between the pitch or character spacing of the tab rack and differently pitched teeth of an escapement rack.

Referring now in detail to the figures in the drawing, there is shown an escapement mechanism, generally

30 indicated 11, and a tabulating mechanism, generally indicated 13, for controlling the movement of a carriage, generally designated by reference character C, which is mounted on a frame, generally designated by reference character F of a typewriter or similar business machine for slidable movement relative thereto. In printing a line of type, the carriage C is moved in a letter feed direction under the control of the escapement mechanism 11 which permits the carriage C to move only one character space at a time, while permitting

35 free movement of the carriage C in the opposite direction during a carriage C return operation. To move the carriage quickly in the letter feed direction to one or more predetermined positions, the tabulating mechanism 13 is actuated to disengage the escapement mechanism 11 and enable the carriage C to slide freely relative to the typewriter frame F until the predetermined position is reached, whereupon the tabulating mechanism 13 operates to arrest the movement of the carriage C and return it to the control of the escapement mechanism 11. Although the present invention will be

40 described in connection with a typewriter having a carriage C for transporting a single print element, it is to be understood that the invention could also be utilized in a typewriter having a reciprocating carriage C for transporting a paper supporting platen. Furthermore, the carriage C and the typewriter frame F as well as other portions of the typewriter are shown only generally since they form no part of the present invention and may be desirably conventional.

45 As shown, the escapement mechanism 11 includes a feed pawl 15 which is pivotally supported about a stud 17 associated with the carriage C for engagement with an escapement rack 19 which may be suitably mounted on the frame F of the typewriter. The feed pawl 15 has a tooth 21 for engaging one of a series of evenly spaced teeth 23 formed on the escapement rack 19, and the feed pawl 15 is urged into engagement with the escape-

ment rack 19 by a spring 25 stretched between a projection 27 of the feed pawl 15 and a suitable portion of the typewriter carriage C. Each of the teeth 23 formed on the escapement rack 19 represents a character space along the line of type, and the distance "a" between the teeth 23 of the escapement rack 19, herein-after referred to as the pitch of the escapement rack, corresponds to the size of the type characters on the print element being transported by the carriage C. During each successive printing operation, the escapement mechanism 11 permits the carriage C to advance in the letter feed direction only one tooth 23 at a time, and no further description of the escapement mechanism 11 is believed necessary since the operation of the escapement mechanism 11 for controlling the movement of the type carriage C relative to the frame F of the typewriter is well-known in the typewriter art.

As also shown, the tabulating mechanism 13 includes a control member 29 in the form of a lever which is movable about the stud 17 associated with the carriage C and carries on one end a tab member 31 for engagement with a plurality of tab stops 33 of a tab rack generally designated by reference character R suitably mounted on the typewriter frame F. The tab stops 33 are equally spaced apart with a spacing "a" corresponding to that of the escapement rack 19, and each of the tab stops 33 may be set, as shown by the tab stop 33', in a conventional manner for engagement by a blade 35 of the tab member 31 during the tabulating operation. The stud 17 is received in a central elongated opening 37 of the control member 29 with one end of the elongated opening 37 normally pressed against the stud 17 by a spring 39 stretched between the control member 29 and a suitable portion of the carriage C for urging the control member 29 in the letter feed direction. The control member 29 has a projecting finger 40 for engaging the feed pawl 15 to disengage the escapement mechanism 11, while a bent ear 41 is formed at the other end for engaging a latching mechanism, generally indicated 43. As shown, the latching mechanism 43 includes an L-shaped lever 45 pivotally supported by a stud 46 on the carriage C with one arm 47 engaging the bent ear 41 of the control member 29 while the other arm 49 is urged toward a stop abutment 51 by a spring 53 stretched between the arm 49 and a suitable portion of the carriage C.

In a tabulating operation, the control member 29 is pivoted from a rest position, as shown in FIG. 1, to an operating position, as shown in FIG. 2, to remove the feed pawl 15 from engagement with the escapement rack 19 and enable the carriage C to slide freely in a letter feed direction toward a set tab stop 33'. The pivoting of the control member 29 places the blade 35 of the tab member 31 in a position for engaging the set tab stop 33', and the control member 29 is held in the pivoted position by the latching mechanism 43 which receives the bent ear 41 in a notch 55 formed in the latching lever 45. Upon engagement of the tab blade 35 with the set tab stop 33', the control member 29 is driven against the urging of the spring 39 until the opposite end of the elongated slot 37 is pressed against the stud 17 to bring the carriage C to a stop. At the same time, the sliding movement of the control member 29 removes the ear 41 from the latching mechanism 43 to enable the control member 29 to pivot and permit the feed pawl 15 to be returned to engagement with the escapement rack 19 under the urging of the spring 25, as

shown in FIG. 3, while the latching lever 45 is pivoted into engagement with the stop abutment 51 under the urging of the spring 53. Subsequently, the control member 29 is pulled in the letter feed direction by the urging of the spring 39 until the end of the elongated slot 37 is pressed against the stud 17 as shown in FIG. 1.

As previously discussed, the single print element of the typewriter may be replaced with another print element having type characters requiring a different or larger character spacing, for example, pica type. To enable the carriage C to be advanced in a letter feed direction in steps corresponding to the spacing of the larger type characters, the escapement mechanism 11 may be modified by replacing the escapement rack 19 having the pitch "a" with an escapement rack 19' having a pitch "b" as shown in FIG. 2. Although not shown, such a substitution may be easily accomplished by pivotally supporting the two escapement racks 19, 19' for alternate movement into operating engagement with the feed pawl 15. However, with the substitution of the escapement rack 19' having the larger character spacing, the settable tab stops 33 no longer have a character spacing corresponding to that of the escapement mechanism 11.

In accordance with the present invention, the tabulating mechanism 13 is designed to compensate for the difference in pitch between the escapement rack 19' and the tab stops 33 so as to enable accurate tabulating operations to be carried out when escapement rack 19' is operably associated with the feed pawl 15. As shown, the tab member 31 is pivotally supported by a stud 32 on the control member 29 and has an arm 57 urged against the control member 29 by a spring 59 stretched between the arm 57 and a suitable portion of the control member 29. In addition, the tab member 31 has another arm 61 carrying a suitable roller 63 for engagement with a tab member control means. As shown, the tab member control means is in the form of a bail 65 having a cyclically repeated camming surface 67 and which may be suitably supported on pivoted arms (not shown) whose free ends are secured to stub shafts 68 on the ends of the bail 65 to permit its pivotal movement under manual control, for example, to a lowered operating position as shown in FIGS. 2 and 3 when the escapement rack 19' having the pitch "b" is brought into operative association with the feed pawl 15.

Accordingly, when a tabulating operation is effected using the escapement rack 19', the pivoting of the control member 29 brings the roller 63 carried by the tab member 31 into engagement with the camming surface 67 of the operatively positioned bail 65 so as to effect an oscillatory movement of the tab blade 35 as the carriage C moves relative to the typewriter frame F. As more particularly shown in FIG. 4, the camming surface 67 of the bail 65 is designed to pivot the tab member 31 so as to bring the tab blade 35 into engagement with set tab stops 33' at character spacings corresponding to the larger pitch of the alternate escapement rack 19'. Upon completion of the tabulating operation, the movement of the carriage C will be returned to the control of the escapement mechanism 11 as previously described, and the tab member 31 will be removed from engagement with the operatively positioned bail 65.

What is claimed is:

1. In a business machine having relatively movable first and second elements, the combination comprising:

an escapement rack associated with said first element for relative movement therewith and having a plurality of teeth formed thereon each defining a character space, 5
 a feed pawl pivotally supported about a point on said second element for relative movement therewith and having a tooth for engaging the teeth of said escapement rack, 10
 said feed pawl being resiliently urged into engagement with said escapement rack for controlling the relative movement between said first and second elements in a letter feed direction, 15
 a control member pivotally supported about the point on said second element for disengaging said feed pawl from said escapement rack during a tabulating operation to permit free relative movement between said first and second elements in the letter feed direction, 20
 a tab rack associated with said first element for relative movement therewith and having a plurality of settable tab stops each corresponding to a character space different from the character space defined by the teeth of said escapement rack, 25
 a tab member having a tab blade for engaging a set tab stop on said tab rack during a tabulating operation, 30
 said tab member being pivotally supported on said control member for enabling the tab blade to be moved relative to said control member on said second element, and
 tab member control means associated with said first element and operable in response to relative movement between said first and second elements during a tabulating operation for pivoting said tab member to alter the position of said second element relative to said first element upon engagement of the tab blade with a set tab stop to compensate for the difference in character spacing between the teeth of said engagement rack and the settable tab stops. 35

2. In a business machine according to claim 1:

5
 10
 15
 20
 25
 30
 35
 40

said tab member having an arm for engaging a camming surface, 5
 said tab member control means including a camming surface for engaging the arm of said tab member to pivot the tab blade in an oscillatory movement during free relative movement between said first and second elements in the letter feed direction, and said camming surface defining an oscillatory movement of said tab blade to compensate for the difference in character spacing between the escapement rack and the tab rack. 10
 3. In a business machine according to claim 2: 15
 said control member being slidably disposed about the point on said second element, latch means operable in response to the pivotal movement of said control member to effect free relative movement between said first and second elements for holding said control member in the pivoted position, and said control member being slidable about the point on said second element in response to the engagement of the tab blade with a set tab stop for being released from said latch means for pivotal movement to enable said feed pawl to reengage said escapement rack. 20
 4. In a business machine according to claim 1: 25
 said control member being slidably disposed about the point on said second element, latch means operable in response to the pivotal movement of said control member to effect free relative movement between said first and second elements for holding said control member in the pivoted position, and said control member being slidable about the point on said second element in response to the engagement of the tab blade with a set tab stop for being released from said latch means for pivotal movement to enable said feed pawl to reengage said escapement rack. 30
